IMPROVEMENT IN ROTARY CULTIVATOR.

JAMES C. FITZGERALD, OF WILLET, NEW YORK.

Letters Patent No. 60,164, dated December 4, 1866.

SPECIFICATION.

TO ALL WHOM IT MAY CONCERN:

Be it known that I, JAMES C. FITZGERALD, of Willet, in the county of Cortland, and State of New York, have invented certain new and useful improvements in Machines for Pulverizing, Digging, and Cleaning the Soil; and I do hereby declare that the following is a full and exact description thereof, reference being had to the accompanying drawings, making part of this specification.

Figure 1 is a longitudinal vertical section of my improved machine.

Figure 2, a perspective view, with the main frame and one driving-wheel removed.

Figure 3, a diagram, showing one of the eccentric bearings resting in the secondary frame.

Like letters of reference indicate corresponding parts in all the figures.

My invention consists in resting the shaft supporting the spiral pulverizing arms in eccentric bearings connected by a lever, whereby the gearing may be disconnected at pleasure; the whole being mounted in a secondary frame beneath the main frame, and adjustable higher or lower by a chain or equivalent connected with the main frame; also, in connecting the draught with the secondary frame in such a manner that it has a tendency to hold the pulverizing arms down in the ground, and furnishes a stiff connection between the main and secondary frames, but still allows the desired adjustment.

As represented in the drawings, A A are the driving-wheels, mounted on an axle, B; and C is the main frame connected with said axle by iron bearings, a a. The main frame is provided with the pole, b, for guiding the machine; and the driving-wheels have the usual points, c c, for producing traction on the ground. Inside the driving-wheels are spur or cog-wheels, D D, turning loosely on the axle. These cog-wheels are connected with the driving-wheels by pawls and ratchets, in such a manner that the parts will engage in going forward, but disengage in going backward; the arrangement being similar to that in common use on harvesters. These cog-wheels are made open, as shown, for the purpose of allowing such dirt as drops upon them from the driving-wheels above to pass through freely. With the cog-wheels gear spur pinions, E E, on a secondary frame, G. This frame is made up of curved arms, d d, jointed to the axle B, and connected by a cross-bar, f, at the rear. By this arrangement it will be seen that as the frame G is adjusted higher or lower the pinions will remain in gear with the cog-wheels, as they are concentric with the axle B. The pinions E are secured fast to the shaft H of the frame G. This shaft is made square in cross-section, and over it are slipped, by square eyes, the pulverizing arms I, being separated by suitable washers, h h, between. The eyes are cut in such form in the several arms that when the arms are in place on the shaft they stand in the spiral form indicated in fig. 2. The arms also stand inclined each side from a vertical line, as indicated by the red line in fig. 2. The opposite ends are provided with suitable points or teeth, i i, for tearing up the soil. The journals of the shaft H rest in eccentric bearings or boxes, k k, situated in the arms d d. These bearings are connected by a lever, K, extending across the frame, in the form of a bail, within reach of the driver. The secondary frame is connected with the main frame above, simply by a chain, L, and hook, m.

The operation of the apparatus, as far as above described, will be readily understood. As the machine goes forward, motion is imparted to the pulverizing arms in the direction indicated by the arrow, fig. 1. These arms being set in a spiral form, they strike into the soil in succession, one after another; the furrows or paths made by the teeth thus corresponding in a degree with the successive furrows of a plough. This action is far superior to that which would be produced if the arms were set in rows, and besides, the draught is lessened in a great degree. By this means it will be seen that a comparatively small number of arms will answer the purpose of many set in any other way. In addition to the above, the setting of the arms in the inclined position before described causes each tooth to strike in a new path from its fellow, thus securing the maximum effect in cutting the soil. By the employment of the secondary frame I not only furnish a convenient attachment and connection for the pulverizer, but I enable the latter to be adjusted higher or lower at pleasure, to suit the different condition of the soil. This is accomplished by simply hooking the chain L higher or lower in the hook m—a very convenient arrangement for the purpose. The employment of the eccentric bearings k k, in which the journals of the pulverizer shaft rest, and the lever K, connecting them, enable me at any time to throw the pulverizer out of gear by a simple movement of the hand. This is of much importance in going into the field and in transportation, and also in passing obstructions, when the rapid motion of the arms would cause breakage. This combined arrangement of the secondary frame, concentric with the main axle, and adjustable higher or lower, with the pulverizer shaft, resting in the eccentric bearings, and capable of being thrown out of gear by a movement of

the lever, and with the arms themselves set in the spiral and inclined manner described, presents features never before known in any similar machine, to the best of my knowledge. In addition to simply pulverizing and digging the earth, my machine, by the peculiar action of the arms *II*, and the teeth upon its ends, will throw up all weeds and stalks upon the surface, free of dirt, where they soon die; and in this manner it acts as a thorough cleaner of the soil. To the arms *d*, of the secondary frame, a little back of its connection with the axle *B*, are secured chains, *M M*, connecting at the opposite ends with arms *N N*, pivoted at *n*, to the main frame, and having stops, *o*, which gauge the extent of their movement forward, as will presently be described. With these arms is also connected, in front, a double-tree, *O*, by links, *p p*, or equivalent, to which double-tree the whiffle-trees are attached in the usual manner. By this arrangement it will be seen that the draught through the chains *M M* will be applied to the secondary frame *G*, a little back and downward of its connection with the main axle; and therefore the tendency will be to draw the pulverizing arms downward into the earth and keep them there. This action will tighten the chain *L* in the rear, and furnish a stiff connection throughout the machine, as effective as if the whole were rigidly connected. At the same time, if undue power is applied the gauge arms *N N* will strike the stops *o o*, as indicated by the red lines in fig. 1, and the draught will then apply on the main frame *C*. This enables me to graduate the power exactly as desired.

What I claim as my invention, and desire to secure by Letters Patent, is—

The arrangement of the spirally and inclined armed pulverizer *H*, resting in the eccentric bearings *k*, when said parts are combined with a vertically adjustable frame, *G*, suspended from the main frame and concentric with the axle, as set forth.

I also claim, in combination with the frames *G* and *C*, the draught chains *M*, and the gauge arms *N*, operating substantially as and for the purpose specified.

In witness whereof I have hereunto signed my name in the presence of two subscribing witnesses.

J. C. FITZGERALD.
